(57) **CLAIM**

The ornamental design of a vehicle headlight, as shown and described.

DESCRIPTION

FIG. 1 is a perspective view of a left vehicle headlight (the right vehicle headlight is a mirror of the left and is not illustrated but nonetheless covered by this patent);

FIG. 2 is a front elevational view of the vehicle headlight;

FIG. 3 is a top plan view of the vehicle headlight;

FIG. 4 is a bottom plan view of the vehicle headlight;

FIG. 5 is a right elevational view of the vehicle headlight; and,

FIG. 6 is a left elevational view of the vehicle headlight.

Portions surrounded by broken lines are not claimed.
